UNITED STATES PATENT OFFICE.

SAM BOWHALL, OF EDMORE, MICHIGAN.

KITCHEN-CABINET.

SPECIFICATION forming part of Letters Patent No. 429,602, dated June 10, 1890.

Application filed February 21, 1890. Serial No. 341,256. (No model.)

To all whom it may concern:

Be it known that I, SAM BOWHALL, a citizen of the United States, residing at Edmore, in the county of Montcalm and State of Michigan, 5 have invented a new and useful Kitchen-Cabinet, of which the following is a specification.

The invention relates to improvements in kitchen-cabinets.

10 The object of the present invention is to provide a cabinet of simple and inexpensive construction, in which a flour-sifter will be conveniently arranged and in which will be a number of compartments adapted to contain various articles necessary for household use.

15 The invention consists in the construction and novel combination and arrangement of parts hereinafter fully described, illustrated 20 in the accompanying drawings, and pointed out in the claims hereto appended.

In the drawings, Figure 1 is a perspective view of the kitchen-cabinet constructed in accordance with this invention. Fig. 2 is a 25 central vertical sectional view. Fig. 3 is a horizontal sectional view. Fig. 4 is a vertical sectional view on line $y-y$ of Fig. 3. Fig. 5 is a detail view of the bearing-plate. Fig. 6 is a detail view of one of the agitators. Fig. 30 7 is a partial transverse section of the top of the cabinet.

Referring to the accompanying drawings, 1 designates a casing or frame, which is constructed of suitable material, preferably light 35 wood, and is divided at the top by transverse partitions 2 and 3, from which the sides 4 and the front and rear faces 5 and 6 are suspended bins 7, 8, and 9. The bin 7 is the largest and is centrally arranged between the 40 two smaller bins 8 and 9 and is designed to contain flour, and is provided at its lower end or bottom with a curved sifter 10. The sides of the bin near the bottom gradually taper toward the curved sieve to direct flour 45 or other contents thereto, and the bin is provided with a pair of agitators 11 and 12, that are similar in construction and are arranged one above the other and are adapted to prevent the flour becoming caked, and the lower 50 one is arranged to engage the sifter and move

across the entire surface of the same to cause the flour of the bin to fall through into a large drawer 13, placed below the bin in the lower part of the frame or casing 1. The body of each agitator is approximately rectangular, and is composed of parallel side bars 14 and slightly-curved or angular end pieces 15 and rods 16, that extend out from the end pieces at points about midway their length, and these rods have their ends rounded and 55 journaled in plates 17 and 18, that are secured to the front and rear faces of the frame or casing. These plates consist of a pair of disks provided with centrally-arranged bearing and connected by parallel bars, and the 60 rear plate 18 has its central bearings formed by integral caps that inclose the ends of the rods of the agitators and prevent the entrance of dust and extraneous matter to the bin and preserve the flour or other contents of 65 the bin perfectly pure. The rods of the agitators that are arranged in the bearings of the plate 17, that is secured to the front face of the frame or casing, project beyond the 70 plate and have secured to them a pair of similar cog-wheels 19 and 20, that mesh and impart motion to both of the agitators. One of the cog-wheels is provided with a handle, by means of which the agitators are operated. The sieve 10 is arranged concentric with the 75 lower agitator, and during the rotation of the latter the side bars 14 come in contact with the sieve 10 and move across the entire face of the same and cause the flour to pass through the perforations thereof, and the 80 end pieces 15 have sufficient curve or slant to clear the sloping sides of the bin. The bins 8 and 9 are similar in construction, and are adapted to contain meal, buckwheat, or 85 similar articles, and have the lower portion 90 of their front and rear faces sloping to contract the bottom 21, which is provided with a central opening 22, that is normally closed by a slide 23. The slide 23 is operated by a rod 24, that extends through the casing and 95 terminates in a knob or handle 25, and when it is desired to obtain a quantity of the contents of the bin the slides are drawn aside and the openings are exposed and the contents fall in drawers 26 and 27, arranged be- 100

neath the bins for that purpose. The bins are closed at the top of the casing by separate doors, which enable the bins to be opened singly and prevent the contents of one being 5 mixed with the contents of the others.

The casing or frame 1 is provided below the drawers 26 and 27 with series of similar drawers that are designed to receive various articles of household goods.

10. What I claim is—

1. The combination of the frame or casing provided with the plates 17 and 18, having bearings, a bin having its lower end tapering and provided with a curved sieve forming the 15 bottom of the bin, the agitators arranged in the same vertical plane and journaled in the bearings of said plates 17 and 18, one of the agitators being arranged adjacent to the sieve and adapted to engage the entire 20 surface of the same, and the cog-wheels 19 and 20, secured to the ends of the agitators, substantially as and for the purpose described.

2. The combination of the frame or casing provided with plates 17 and 18, having bearings, a bin having its lower portion tapering 25 and provided with a curved sieve, the agi-

tators arranged in the same vertical plane, and comprising the parallel side bars, the end bars, and the rods 16, journaled in the bearings of the plates, and the cog-wheels secured to the rods 16 and meshing with each other, substantially as described.

3. The combination of the frame or casing, the plates 17 and 18, secured to the front and rear faces thereof, and composed of the disks 30 provided with central bearings and the side bars connecting the disks, a bin provided at its lower end with a curved sieve, the agitators journaled in the bearing of said plates 17 and 18, and being composed of the parallel 35 side bars, the end bars, and the rods 16, and the cog-wheels secured to the ends of the rods 16 and meshing with each other and provided with a suitable operating-handle, substantially as described.

In testimony that I claim the foregoing as my own I have hereto affixed my signature in presence of two witnesses.

SAM BOWHALL.
